FUEL IGNITER

Johann Gunther Cohn, East Orange, N. J., assignor to Baker & Co., Inc., Newark, N. J., a corporation of New Jersey

Application November 26, 1948, Serial No. 62,190

3 Claims. (Cl. 219—32)

1

The present invention deals with the ignition of fuels and is concerned more particularly with the provision of an automatic igniter for fuels, such as organic inflammable gases, in finely divided state.

Efforts have been made for many years to replace the open-flame gas pilot light by more economic and safer means. Electric ignition by means of an electrically heated incandescent wire or the like brought to the ignition temperature of the fuel is, of course, superior to the open pilot light insofar as safety is concerned, but otherwise only substitute waste of electrical energy for waste of fuel energy and, furthermore, requires an expensive mechanism.

In my co-pending applications, No. 792,673 and No. 792,674, I have described automatic igniters in the form of a catalyst of fine diameter wire in the shape of a coil electrically heated to a temperature substantially below the ignition temperature of the fuel, the coil of the igniter of application No. 792,674 being more particularly so constructed as to constitute a heterophase catalyst wherein the catalytic reaction starts at one phase and ignition occurs at another phase. Such electrically heated catalytic igniter constitutes the first practical automatic igniter capable of reliably igniting, on contact, finely divided fuels in a flowing fuel-air mixture in which the fuel comprises inflammable materials difficult to ignite, such as such saturated hydrocarbon gases as butane, propane, or even methane, or the like.

The present invention deals more specifically with a further improvement upon the automatic igniter of my present co-pending applications above referred to.

The chief object of this invention is to provide an automatic catalytic igniter which shall be highly superior in its function and efficiency in the ignition of fuels most difficult to ignite, such as natural gas and in particular a gas as difficult to ignite catalytically as methane, and which, in this function and its efficiency, is even superior to the igniters shown more specifically in my co-pending application No. 792,674. It is another object of this invention to provide such igniter for such flowing fuel-air mixtures comprising saturated gaseous hydrocarbons or other finely divided organic fuels wherein such mixtures may be substantially devoid of free hydrogen or wherein at least the free hydrogen, if any, is practically ineffective in the ignition process. It is another object to provide a highly efficient automatic igniter, of the catalytic type, suitable for the safe and reliable ignition of any and all fuel-air

2

mixtures containing inflammable constituents adapted to be catalyzed. It is a further object of the invention to provide such igniter which shall operate reliably over a wide range of fuel-air compositions. It is another object of this invention to provide an automatic igniter which shall be easy and simple to manufacture. Other objects and advantages of the automatic fuel igniter of my invention will appear from the description thereof hereinafter following.

As in my co-pending applications referred to, the catalyst wire of the igniter must have a very small diameter and be shaped to form a coil. The wire consists, or has at least a surface, of catalyst metal adapted to catalyze the fuel in the fuel-air mixture in a flameless combustion, the catalyst comprising such metal as platinum or other metal of the platinum group or alloy thereof. The coil is electrically heated to a temperature substantially below the ignition temperature of the finely divided fuel, such as methane or other saturated hydrocarbon gas, in the fuel-air mixture.

The specific feature of the igniter of this invention is that the coiled wire is in turn shaped into a coiled or other suitable structure—i. e. a primary coil of fine coil diameter is formed, e. g. into a secondary coil of larger coil diameter, as for instance a "coiled coil."

Reference is made to the drawings, forming part hereof, in which:

Figure 1 represents a diagram of an ignition system embodying the igniter,

Figure 2 represents an enlarged elevational view, shown schematically, of the igniter of this invention, and

Figures 3 and 4 represent like views of modified embodiments of the igniter.

Referring more particularly to Figure 1, the igniter 1, illustrated schematically only, is shown within a dual flash-back system. The burners, to be lit, are indicated at 2 and 2'. A gaseous mixture flowing from the flash-back ports 3 and 3', enters the two flash-back tubes 4 and 4' and flows toward and into contact with the igniter 1 where it is, on contact, ignited. The flame then travels in flash-back manner back to the flash-back ports 3 and 3' and there establishes continuously burning flames by which the gas flowing through the burners 2 and 2' becomes ignited. While in this Figure 1, I have illustrated a 2-burner unit, it will be understood that the same principle applies to the ignition of other multiple burner units or a single burner unit.

Referring now more particularly to Figures 2, 3 and 4, the igniter itself consists of a coiled wire

5 of catalyst metal, e. g. platinum or metal of the platinum group or alloy thereof, shaped into a secondary form comprising a twisted structure of variated form. In Figure 2, the structure is shown as a "coiled coil" with a plurality of turns and in Figure 3 as a plurality of V-bends and in Figure 4 as a plurality of simple bends forming at least one S-shaped structure. The structures shown in Figures 2-4 are intended as illustrations, other twisted shapes and structures of the fine coiled wire being possible, such, e. g. as a simple loop.

The "coiled coil" in which a densely wound primary coil of small diameter is wound into the shape of a secondary coil having turns of larger diameter, relative to the diameter of the turns of the primary coil, and other such twisted structures, as shown, are of the nature of a heterophase catalyst in which the catalytic reaction starts at one phase and is accelerated to ignition at another phase activated by the phase at which the reaction starts.

The wire itself of the igniter must have a very fine diameter, of the order of a minimum of about 0.001", and a maximum of about 0.003". The primary coil may have an inner diameter of from about 0.002" to about 0.015" and a spacing of from about 50 to about 400 turns per lineal inch. The secondary coil, or winding, may have an inner diameter of from about 0.01" to about 0.1". For example, when a wire of 0.001" or 0.002" is used, the primary coil may consist of a great number of close turns, e. g. of the order of 135 turns per lineal inch, the turns having an inner diameter of 0.005", whereas the secondary coil, of at least two or more turns, has an inner diameter of about 0.035". The igniter structure is electrically heated, by resistance, to a temperature well below the ignition temperature of the flowing fuel-air mixture and, of course, below the recrystallization temperature of the metal of the structure. Such heating is accomplished with extremely small current of low voltage and low amperage. On contact with the flowing fuel-air mixture, the reaction starts immediately and is almost instantaneously accelerated to ignition with an attendant increase of the temperature of the igniter, whereupon the burning gas is removed from contact with the igniter, as for instance by means of the flash-back system or otherwise. The source of electric power is indicated at 6, which may be either a battery or a transformer, with leads 7 and 7'. The electrical heating may be continuous, or it may be controlled to coincide with the operation of the burner unit or units so as to occur only on opening of gas jets.

The igniter of this invention represents an extremely efficient device for the ignition of flowing fuel-air mixtures, even those wherein the fuel is such difficultly ignitable a fuel as methane.

The igniter of the present invention is superior in reliability of ignition to any other structural form of electrically heated catalytic igniter. In my co-pending application No. 792,674, I have more fully explained the heterophase principle of the catalytic igniter in that the catalytic reaction starts at one phase, the primary phase portion, which in turn heats up fast the secondary phase portion at which thereupon the flameless reaction at the primary phase portion is accelerated to flame formation and ignition. In the instant case, the igniter operates likewise on this heterophase principle. In the formation of the secondary coil or the like, the initially even and uniform

spacing between the turns of the coil is changed to an uneven spacing, the inner parts of the primary turns coming closer together and the outer parts spreading apart, resulting, thus, in a greatly variated structure in which numerous sections of closely spaced turns are adapted to act as primary phases alternating with numerous sections adapted to act as secondary phases, thus affording to the impinging fuel-air mixture a large number of starting points, primary phase, for the reaction and adjacent areas, secondary phase, where the initial reaction can be accelerated to ignition.

Even a mere bend, or loop, of the fine-diameter coil creates an efficient automatic igniter, although the preferred form of igniter in accordance with this invention is one in which the primary coil is shaped into a large-diameter coil or other structural forms having a plurality of primary and secondary phases.

The superiority of the igniter of this invention over other electrically heated catalytic igniters and over other types of such heterophase igniters is evidenced by its performance.

For instance, a 0.002" wire wound into a primary coil having an inside diameter of 0.005", 135 turns to the lineal inch, and then wound into a secondary coil of two or three turns and having an inside diameter of about 0.035" invariably ignited methane in a flowing methane-air mixture on heating with from about 0.25 watt to about 0.6 watt with a voltage of from 1.30 volts, and 0.2 ampere, to 2.5 volts and 0.225 ampere. A straight single coil would be unable to ignite methane under any such or similar conditions.

A similar igniter in the form of the twisted structure of Figure 3 or of Figure 4 operates in like manner. For instance, such igniter of 0.002" wire coiled into a primary coil having an inside diameter of 0.004", 135 turns to the lineal inch, and shaped into the W-structure of Figure 3 and heated with 0.5 watt, or 1.9 volts and .26 ampere, ignited methane in the above-mentioned methane-air mixture instantaneously. The S-structure of Figure 4 requires for like performance a slightly higher power, e. g. 0.55 watt for a wire coil as above stated, or 0.29 ampere and 1.9 volts.

The number of turns of the secondary coil may vary, there being at least two such turns. Normally, it is safest to employ three or four turns and if desired, there may be more such turns of the secondary coil. The voltage and the amperage of the electric heating current, and the total wattage input, must be sufficiently small, correlated to the wire diameter, to maintain the temperature of the coil at the specified low temperature. Generally speaking, the igniter of my invention will not glow when not in contact with the flowing fuel-air mixture, although a slight glow may occur in some cases.

The catalyst metal of which the wire, or at least the surface of the wire, is formed, is usually platinum or an alloy of platinum with another metal of the platinum group, e. g. such alloys of platinum and rhodium or platinum and iridium, the platinum content normally being at least 80% or 90% of the alloy, or with other suitable metal or metals, such for example as nickel, tungsten, and so forth. The wire material may be in the form of a sintered agglomerate of the catalyst metal or metals, with or without other metals, e. g. tungsten, and, preferably, with a small percentage, or fraction of a percent, of refractory oxide distributed therethrough, such as thorium oxide, beryllium oxide and so forth. The wire may have any desired cross-sectional shape,

usually, however, circular. Stranded wire may also be used in the formation of the structural igniter of this invention, in which case the overall thickness of the wire composed of the individual strands should correspond in electrical resistance to that of the wire herein described otherwise; in this case, the individual strands need not necessarily be composed of the same metal but may consist of different metals or compositions.

Experiments with the igniter of this invention have shown, further, that it is far superior to other igniters even in the ignition of city gas, i. e. so-called manufactured gas, which contains a certain amount of hydrogen. In general, in the ignition of such gas, the power input has been found to be about 15% less for ignition by means of the igniter of this invention compared with an otherwise similar simple straight coil, for obtaining ignition. However, the most significant difference is found when the igniter is used for the ignition of such gas in multiple-burner unit, since in such arrangement, see e. g. Figure 1, the combustion products flowing from one ignited flash port, e. g. 3, through flash tube 4 and impinging on the igniter 1, mingle with the gas stream to be ignited which is flowing from flash port 3' through flash tube 4', and tend to blanket the igniter and interfere with the second ignition. A single straight coil is apt to become unreliable, or slower in its ignition action than a coil according to the present invention. The far greater reliability of the present igniter when used to light two or more burners, either together or in succession, is of the greatest importance in assuring maximum safety.

The fuel-air mixtures in the experiments described resulted from a jet of fuel, e. g. methane, through nozzles, into air, and are thus the customary mixtures encountered in practical systems such as gas range burners. The flames were of the characteristic blue color. The pressure of the jet varied over wide ranges as encountered in heating practice.

The manner of connecting the igniter to the source of electric power may be conventional. In Figure 1 I have shown one particularly suitable method of mounting the igniter and connecting it to the electric power. Lead-in wire 7' is connected to a metal sleeve 8 mounted on an insulated base 9, and lead-in wire 7 is connected to a contact 10, in the form of a sleeve, mounted within the base 9 and electrically insulated against the metal sleeve 8. The igniter 1 is mounted between the two leads 11 and 11', which simultaneously serve as supports and which are mounted on a cap 12, lead-in 11' being soldered to or otherwise being in metallic contact with the cap 12 and lead-in 11 being isolated from the cap by means of a sleeve 13 terminating in a metallic tubular extension 14. The cap 12 is pressed down onto and over the sleeve 8, thus bringing the lead-in 11' in contact with the conductor 7' and the lead-in 11 in contact with the contact sleeve 10 and thereby with conductor 7, the entire assembly being held together by the frictional fit of cap 12 over sleeve 8 and of the tube 14 within the sleeve 10.

The igniter may be used in domestic and industrial appliances, such as ranges, stoves, furnaces and so forth, whether direct, as e. g. in top burners of ranges, or indirect, as e. g. in range ovens or furnaces. It may also be used in instruments or other devices wherever it is de-

sired to ignite a gas-air or other fuel-air mixture. The source of electric power may be the line supply, with an interposed resistor or suitable transformer, or a battery, as may be desired. 5 The electrical heating of the igniter may be continuous or limited to coincide with the presence of the air-fuel mixture at the time ignition is desired. As in my preceding applications, above referred to, the fuel-air mixture is withdrawn 10 from contact with the igniter after ignition has occurred, as e. g. by means of the flash-back system. The igniter may also be used for the ignition of a gas which in turn is used for the ignition of another fuel which by itself is either too 15 difficult to ignite or in which ignition is too unreliable.

What I claim is:

1. An automatic igniter for organic fuels in finely divided state capable of being catalytically oxidized in a flowing fuel-air mixture in the presence of a catalyst, comprising an electrically heated heterophase catalyst having at least a primary phase portion to initiate the catalytic oxidation and a secondary phase portion to be activated by the heat of the reaction at the primary phase portion and thereupon to complete the catalytic oxidation to the state where the flameless combustion of the catalytic oxidation is converted into flame combustion, the said catalyst consisting of a closely spaced helical coil of catalyst metal, the wire of said coil having a diameter not in excess of about 0.003", said coil being in turn formed into a coil having a plurality of turns, a source of electrical power connected to said coil to heat said coil to a temperature substantially below the ignition temperature of said fuel in said fuel-air mixture and below the recrystallization temperature of said catalyst metal, and means for terminating the contact between the catalyst and the ignited fuel.

2. An automatic igniter for organic fuels in finely divided state capable of being catalytically oxidized in a fuel-air mixture in the presence of a catalyst, comprising an electrically heated heterophase catalyst taken from the group of metals of the platinum group and alloys thereof, having at least a primary phase portion to initiate the catalytic oxidation and a secondary phase portion to be activated by the heat of the reaction at the primary phase portion and thereupon to complete the catalytic oxidation to the state where the flameless combustion of the catalytic oxidation is converted into flame combustion, the said catalyst consisting of a closely spaced helical coil of said catalyst metal, the wire of said coil having a diameter not in excess of about 0.003", said coil being in turn formed into a coil having a plurality of turns, a source of electrical power connected to said coil to heat said coil to a temperature substantially below the ignition temperature of said fuel in said fuel-air mixture and below the recrystallization temperature of said catalyst metal, and means for terminating the contact between the catalyst and the ignited fuel.

40 3. An automatic igniter for organic fuels in finely divided state capable of being catalytically oxidized in a fuel-air mixture in the presence of a catalyst, comprising an electrically heated heterophase catalyst taken from the group of metals of the platinum group and alloys thereof, having at least a primary phase portion to initiate the catalytic oxidation and a secondary phase portion to be activated by the heat of the reaction at the primary phase portion and thereupon to complete the catalytic oxidation to the state where the flameless combustion of the catalytic oxidation is converted into flame combustion, the said catalyst consisting of a closely spaced helical coil of said catalyst metal, the wire of said coil having a diameter not in excess of about 0.003", said coil having an inner diameter of from about 0.002" to about 0.015" and a coil spacing of from about 50 to 400 turns per inch, said coil being in turn formed into a larger coil having an inner diameter of from about 0.01" to about 0.1", a source of electrical power connected to said coil to heat said coil to a temperature substantially below the ignition temperature of said fuel in said fuel-air mixture and below the recrystallization temperature of said catalyst metal, and means for terminating the contact between the catalyst and the ignited fuel.

45 4. An automatic igniter element for organic fuel in finely divided state capable of being catalytically oxidized in a flowing fuel-air mixture in the presence of a catalyst, comprising a catalyst consisting of a closely spaced helical coil of metal taken from the group of metals of the platinum group and alloys thereof, the wire of said coil 50 having a diameter not in excess of about 0.003",

said coil being in turn formed into a coil having a plurality of turns, a mounting for said catalyst and including lead wires to opposite ends of said coil for connection to a source of electrical power of such order of magnitude as to heat said coil to a temperature substantially below the ignition temperature of said fuel in said fuel-air mixture and below the recrystallization temperature of said catalyst metal.
